UNITED STATES PATENT OFFICE.

HENRY C. POMEROY, OF CHICAGO, ILLINOIS.

RIVETING-MACHINE.

SPECIFICATION forming part of Letters Patent No. 699,707, dated May 18, 1902.

Application filed October 26, 1900. Serial No. 34,501. (No model.)

To all whom it may concern:

Be it known that I, HENRY C. POMEROY, a citizen of the United States, residing at Chicago, in the county of Cook, State of Illinois, have invented certain new and useful Improvements in Adjustable Riveting-Machines, of which the following is a specification, reference being had therein to the accompanying drawings.

10 This invention relates to adjustable riveting-machines, and particularly to such a machine in which the anvil or die may be adjusted in its relation to the plunger for use with different lengths of rivets.

15 The invention has for its object to provide a device for quickly adjusting an anvil or die and holding the same in an adjusted position, so that the machine is adapted to operate with different lengths of rivets.

20 A further object of the invention is to provide an improved structure of casting or housing adapted to receive and contain the operating parts in the most economical manner and in the smallest possible space, so as to 25 provide a tool which can be operated in the hands of the user or attached to a foundation.

Other objects and advantages of the invention will hereinafter appear in the following 30 description, and the novel features thereof will be particularly pointed out in the appended claims.

In the drawings, Figure 1 represents a side elevation of the device with the anvil shown adjusted to an advanced position and the 35 plunger lowered in dotted lines. Fig. 2 is a perspective of the casting adapted to receive the parts of this invention. Fig. 3 is a side elevation with parts in section showing the plunger and die in position when a rivet has 40 been set, and Fig. 4 is a detail perspective of the die-adjusting lever and cam.

Like letters of reference indicate like parts throughout the several figures of the drawings.

45 In the drawings the letter A represents a casting which is of particular construction for use in connection with the present invention. This casting is provided with a base A', having a curved rear outline, as shown in 50 Fig. 2, whereby it is adapted to be grasped in the hand if the tool be used as a hand device, and the forward end of this base is provided

with suitable securing-lugs A², projecting laterally therefrom. At the upper portion of the casting a neck A³ is formed, and extending upwardly therefrom are the pivoting-ears A⁴, adapted to receive the die-adjusting device B. Under these lugs and the extended neck a plunger-case A⁵ is formed and at its upper portion an apertured face-block A⁶ is 60 provided upon which the material may rest. In the curve of the neck and at one side thereof of a lateral rib or projection A⁷ is provided, which acts as a stop to limit the upward movement of the operating-lever C for the plunger. 65 This casting may be apertured in any desired manner and at suitable positions to reduce the weight thereof and economize in the manufacture while retaining sufficient rigidity and strength for the purposes of the invention. 70 The brace-rib A⁸, which connects the base A' with the rear of the neck A³, may be suitably curved, so that the lower portion lies in a different vertical plane from the upper portion, and thus permit the free operation of the 75 plunger-lever in the lower portion of the casting. At the outer end of the neck A³ and at the lower portion of the ears A⁴ a die or anvil D is mounted, which may be of any desired construction, but in the present instance 80 is shown as provided with a laterally-extending head D', between the under face of which and the upper face of the casting an elevating-spring D² is located, so as to normally raise the die and hold the same in contact with the 85 adjusting-faces B' upon the adjusting device B.

It will be obvious that this device may be of various constructions; but in the present illustration of the invention it is shown as 90 provided with a pivoted lug B², journaled at the upper portion of the lugs or ears A⁴ and provided with an operating-lever B³. When journaled in this position, the several faces B' are at different distances from the pivot 95 B², respectively, so as to have the effect of a cam or eccentric in advancing the anvil or die for different lengths of rivet, it being understood that the movement of the plunger is limited to a predetermined extent. These 100 faces B' are preferably squared, so as to readily hold the die in its adjusted position and prevent any further movement of the adjusting device until moved by the operator. Co-

operating with this anvil or die is a plunger E, provided with a transverse head E' and a retracting-spring E², bearing against one face of said head and lying within a suitable recess A³, formed in the casing A⁵ at the base of the casting. This plunger reciprocates through the apertured face A⁶, upon which the work is adapted to rest. The plunger is actuated by any suitable form of lever—for instance, a lever C, pivoted by means of a bolt C', passing through the lever and casing. This bolt is also adapted to hold in position the cover-plate F, which fits the face of the casing A⁵ and protects and conceals the operating mechanism for the plunger. The inner end of the lever C is formed with an angle-arm C², adapted to operate against the under face of the plunger-head E' and elevate the same when the outer end of the lever is depressed. When pressure is relieved from this outer end of the lever, the spring E² retracts the plunger and elevates the outer end of the lever until the same comes into contact with the rib A⁷ of the neck, which acts as a stop to limit the upward movement of the lever.

In the operation of the invention it is essential that the anvil or die be located a proper distance above the face A⁶, through which the plunger operates for each thickness of material used, and consequently the length of rivet employed. This is essential for the reason that if the material be not held against upward movement when the rivet rises with the plunger the rivet will probably be turned over or partially headed before it can force its way through the material. When the parts are in the position shown in Fig. 1, the rivet is dropped into the aperture and rests upon the face of the plunger E. The material to be riveted is then placed upon the face A⁶ and the anvil or die adjusted by means of the lever B³, so as to be in intimate proximity to the upper face of the material to be riveted. The outer end of the lever C is then depressed, which raises the plunger and the rivet, forcing the latter through the material and into contact with the heading-face of the die or anvil. If very thick material is to be riveted, the die would be adjusted as shown by full lines in Fig. 1, while if the material is of a thin character the die would be adjusted closer to the face A⁶, as shown by dotted lines, and for various thicknesses of material the intermediate faces B' can be employed. In operating the invention the same may be grasped in one hand of the operator, with the fingers beneath the rearwardly-extending base A' and the thumb upon the end of the lever, while, if preferred, the casting may be secured to a foundation by means of the lugs A² and the plunger operated by pressure upon the outer end of the lever C. It will be apparent that the various degrees of adjustment for the anvil or die are secured by a simple and ready movement of the lever B³, so as to bring the va-

rious faces of the cam device into contact with the head D' of the anvil to advance the same, and when the reverse movement is desired the spring D² lifts the anvil and holds the same constantly in contact with the faces B'. It may be stated that other devices than the lever and cam structure here shown may be provided for advancing and holding the die in a step-by-step progressive movement.

It is obvious that changes may be made in the details of the configuration of the casting and other parts either for the purpose of ornamentation, economy of construction, or the attachment of auxiliary devices without departing from the spirit of the invention as defined by the appended claims.

Having described my invention, what I claim is—

1. In a riveting-machine, the combination with a slidable die, of a device mounted above the die having independent faces for moving the same in one direction successive distances relative to different lengths of rivets, and a plunger having a fixed length of travel and adapted to coöperate with said die; substantially as specified.

2. In a riveting-machine, the combination with a movable die, of a device mounted above the die for moving the same in one direction and having a series of contact-faces at different distances from a fixed point relative to different lengths of rivets, a plunger adapted to coöperate with said die and having a fixed length of throw, means for retracting said die in the reverse movement of the advancing device, and means for retracting said plunger and its operating-lever when pressure is relieved from the same; substantially as specified.

3. In a riveting-machine, the combination with a casting or housing, of a movable die, a rotatable adjusting device adapted to contact with said die having a series of faces disposed at different distances from a pivotal point relative to different lengths of rivets and adapted to be successively brought into contact with said die, and a movable plunger coöperating with said die; substantially as specified.

4. In a riveting-machine, the combination with a casting or housing, of a movable die, an adjusting device adapted to contact with said die having a series of faces disposed at different distances from a pivotal point relative to different lengths of rivets and adapted to be successively brought into contact with said die, a movable plunger coöperating with said die, a spring for retracting said die, a spring for retracting said plunger, an operating-lever pivoted in said casting and having a projection adapted to engage and move said plunger; substantially as specified.

5. A casting for a riveting-machine having a horizontally-disposed base portion, a casing disposed at the forward end of said base, an apertured face at the upper portion of said casing, a neck provided with pivoting-ears

and extended over said apertured face, a stop-rib disposed at one side of said neck, a rear-wardly-extending base portion, and a rib deflecting laterally from the center of said neck 5 to one side of said base; substantially as specified.

6. In a riveting-machine, a casting or housing provided with a casing at its forward portion and pivoting-ears above said casing, an 10 adjustable die slidably mounted between said ears, a cam device pivoted at the upper portion of said ears and provided with a series of faces at different distances from the pivot, relative to different lengths of rivets, a spring 15 for retracting said die, and a plunger for cooperating with said die; substantially as specified.

7. In a riveting-machine, a casting or housing provided with a casing at its forward portion and pivoting-ears above said casing, an 20 adjustable die slidably mounted between said ears, a cam device pivoted at the upper portion of said ears and provided with a series of faces spaced from said pivot at distances 25 relative to different lengths of rivets, a spring for retracting said die, a plunger slidably mounted at the upper portion of said casing, a spring for retracting said plunger, an operating-lever pivoted to said casing and provided with a projection lying beneath said 30 plunger; substantially as specified.

8. In a riveting-machine, the combination with a movable die, of a pivoted cam device having a series of flat faces spaced from the 35 pivot at distances relative to different length of rivets adapted to bear against a portion of said die to advance the same to different degrees, and a plunger having a fixed length of travel; substantially as specified.

40 9. In a riveting-machine, the combination with a casting or housing provided at its forward portion with a casing and a neck having pivoting ears or lugs, of a die slidably

mounted between said ears and having a transverse head, a retracting-spring disposed 45 between said head and casting, an adjusting-cam device pivoted above said die and having a series of flat faces spaced from the pivot at distances relative to different lengths of rivets, a plunger slidably mounted in said casing beneath said die, a laterally-extending head to said plunger, a spring disposed between said head and casing, and an operating-lever pivoted to said casing and provided with an arm beneath said plunger; substantially 50 55 as specified.

10. In a riveting-machine, the combination with a casting or housing provided at its forward portion with a casing and a neck having pivoting ears or lugs, of a die slidably 60 mounted between said ears and having a transverse head, a retracting-spring disposed between said head and casting, an adjusting-cam device pivoted to said ears above said die and having a series of flat faces spaced 65 from the pivot at distances relative to different lengths of rivets, a plunger slidably mounted in said casing beneath said die, a laterally-extending head to said plunger, a spring disposed between said head and casting, an operating-lever pivoted to said casing and provided with an arm beneath said plunger, a stop-rib extending from the casting above the outer end of said plunger-lever, a cover-plate for said casing, a bolt for said 70 operating-lever passing through the casting, lever and cover-plate, and a projecting arm at the base of said casting lying beneath the extended free end of the plunger-operating lever, substantially as specified.

In testimony whereof I affix my signature in presence of two witnesses.
